MACHINE FOR FINISHING OR GRINDING
ARCUATE SURFACES

John Van Buren, Brooklyn, N. Y.

Application November 24, 1945, Serial No. 630,651

7 Claims. (Cl. 51—101)

1

This invention relates to a machine for finishing or grinding arcuate surfaces.

The invention has been particularly worked out in connection with a machine for grinding or finishing the arcuate surfaces of a cam groove. It is a comparatively simple matter to grind or finish evenly and smoothly concentric portions of cam grooves but it is difficult to give an even, smooth finish to the portions of the cam groove which are eccentric to or irregularly related to the axis of rotation of the cam.

This invention has for its object to automatically adjust or regulate the relative positions of a cam or a member having a curved surface to be finished and the finishing member or tool, such as a grinder, in such a manner that the walls of the cam groove or the arcuate or curved surfaces to be finished will be evenly and smoothly finished.

Another object of the invention is to provide tool adjusting mechanism for a rotatable tool so constructed and arranged that the center of rotation of the tool and the point of contact of the tool periphery with the curved or arcuate surface being finished will be automatically maintained on a radius of curvature of the surface being ground.

Further objects of the invention will appear from the following specification taken in connection with the drawings which form a part of this application, and in which

Fig. 1 is a vertical sectional elevation of a machine constructed in accordance with the invention;

Fig. 2 is a top plan view of the machine shown in Fig. 1, parts being omitted for the sake of clearness;

Fig. 3 is an elevational view looking in the opposite direction from Fig. 1 and showing particularly the driving connections for reciprocating the tool, parts being omitted for the sake of clearness;

Fig. 4 is a vertical sectional elevation taken substantially on line 4—4 of Fig. 1, looking in the direction of the arrows;

Fig. 5 is a transverse sectional plan taken substantially on line 5—5 of Fig. 4, looking in the direction of the arrows;

Fig. 6 is an elevational view taken substantially on line 6—6 of Fig. 1, looking in the direction of the arrows;

Fig. 7 is a vertical elevational view, partly in section, taken substantially on line 7—7 of Fig. 1, looking in the direction of the arrows;

Fig. 8 is a sectional elevation taken through the control cams and the mounting thereof;

Fig. 9 is a diagrammatic elevational view illustrating the cam to be finished, grinding wheel, and showing the angular adjustments of the grinding wheel support;

Fig. 10 is a diagrammatic elevational view illustrating the cam which controls the raising and lowering of the cam having a groove to be ground; and

Fig. 11 is a diagrammatic elevational view illustrating the cam which automatically controls the oscillation of the grinding wheel.

The invention briefly described consists of a machine having a support for the cam having the groove to be finished, a tool support or a support for the grinder, and two sets of automatically operated control mechanisms, one set being controlled in its operation by a cam which causes the cam having the groove to be finished to be vertically adjusted to maintain the rotatable finishing tool or grinding wheel in contact with the surface to be finished and the other set being automatically controlled by a second control cam which oscillates the tool support and, therefore, the tool, in such a manner as to always maintain the point of contact of the periphery of the grinding wheel or tool and the axis of rotation of the grinding wheel or tool on a radius extending from the point of contact to the center of curvature of the surface being finished. Further details of the invention will appear from the following description.

In the particular embodiment of the invention illustrated in the drawings, the machine is mounted on a base or table 20, on one end of which is mounted a vertical casing 21. In the casing 21 are mounted two vertical posts 22 and 23 and on these posts there is mounted for vertical reciprocation, a carriage 25. The carriage 25 has mounted at the bottom and top thereof, two sets of rollers, the rollers at the top of the carriage being designated 26 and 27 and the rollers at the bottom being designated 28 and 29. These rollers engage the oppositely facing inside cylindrical portions of the posts 22 and 23 and center the carriage between the posts.

The carriage also carries two other sets of rollers adjacent the lower end thereof and adjacent the upper end thereof. The two sets of rollers at the lower end of the carriage are shown in the section illustrated in Fig. 5, one set being indicated at 30 and 31 and the other set being shown at 32 and 33. The upper sets of rollers corresponding to the rollers 30, 31, 32 and 33 are mounted on

the carriage in the same manner as the lower set, one pair of the upper set being shown at 35 and 36 and the other pair being directly in back of this pair, viewing Fig. 4, one of the rollers of the other pair being shown at 37 in Fig. 1.

By means of the rollers above described, the carriage 25 is guided in its vertical reciprocation. The weight of the carriage and the parts carried thereby is partially counterbalanced by a weight W, shown in Fig. 4; which is connected by a cable 10 around pulleys or wheels 41 and 42 to the upper end of the carriage, as shown at 43.

The carriage 25 has laterally extending guide brackets 45 and 46, as shown in Fig. 1, in which is slidably mounted a vertical reciprocatable bar 47, this bar being supported by and pulled upwardly by springs 48 and 49.

Raising and lowering control mechanism

The carriage 25 is provided with bearings 50 and 51 in which is rotatably mounted a shaft 52 on the outer end of which is secured the cam C having a groove 53, the walls of which are to be ground or finished. The shaft 52 has mounted thereon a worm gear 55 which meshes with a worm 56 carried by a shaft 57 mounted in a suitable bearing 58 which is connected to and carried by the carriage 25. The shaft 57 has a bevel gear 60 at the lower end thereof, viewing Fig. 4, and this gear meshes with a bevel gear 61 carried by a shaft 62 mounted in a bearing on bracket 59 carried by and connected to carriage 25. Shaft 62 is connected by a universal joint 63 and a telescopic driving connection 64 to a shaft 65, which in turn is connected by a universal joint 66 to a shaft 67 which is driven by a motor M.

Through the driving connections just described, the motor drives the shaft 52 and thus rotates the cam C having the groove 53 to be finished.

The carriage 25 is controlled as to its vertical adjustment by means of a cam 70 secured to a sleeve 71 pinned to the shaft 52 (see Fig. 8). The cam 70 is in turn supported on a roller 80 rotatably mounted in the upper end of a post 81 which extends upwardly through the table 20 and bottom of the casing 21. This post 81 is vertically adjustable in the following manner. The lower end of the post is threaded into a sleeve 82 which is rotatably mounted in a bracket 83 in such a manner that the sleeve can rotate but cannot move axially. The sleeve 82 has mounted thereon a worm gear 84 which meshes with a worm 85 carried by a spindle 86, to the outer end of which is secured a dial or handle 87. By rotating the dial 87 the sleeve 82 will be rotated and will adjust the post 81 vertically, thereby raising or lowering the roller 80 which supports the cam 70, and the vertical position of the cam 70 determines the vertical position of the carriage 25 and of the cam C which is carried by the shaft 52 mounted in bearings carried by the carriage 25. As the shaft 52 is rotated in the manner above described, the cam 70 will also be rotated. This cam is supported on roller 80 and since the cam is non-circular, as the cam rotates the shaft 52 and work C will be raised or lowered in accordance with the contour of cam 70.

If a single cam surface were being ground, instead of a cam groove, the grinding wheel could be made the same size as the follower on the control cam 70 and this cam alone could control the movement of the cam C to be ground. However, when a cam groove is being ground, the grinding wheel must have a diameter materially smaller

than the width of the groove and the axis of the grinding wheel must be angularly shifted when the curvature or arc of the cam changes centers and radii, or the grinding wheel will not grind the true arc.

Angular adjustment control mechanism for tool support and tool

The tool, which in this instance consists of a grinding wheel 90 carried by a shaft 91, is mounted in the manner hereinafter described in a bracket which is angularly adjusted and is, through intermediate connecting mechanism, supported on a casing 92 mounted on the table 20. The casing 92 is provided with suitable bearings 93 for a shaft 94, on the outer end of which is mounted a sprocket wheel 95 which is connected by a chain 96 to a sprocket wheel 97 carried by the upper end of the casing 92. The sprocket wheel 97 is mounted on a shaft 98 which is connected by a universal joint 99 and a telescopic driving connection 100 to a shaft 101, which in turn is connected through a universal joint 102 to a shaft 103 mounted in bearings 104 formed on the carriage 25. The opposite end of the shaft 103 has secured thereto, a spur gear 106. This gear meshes with a rack 107 formed on the vertically reciprocatable bar 47. The bar 47 has mounted thereon and extending laterally therefrom, a boss 108, on the outer end of which is mounted a roller 109. The roller 109 is held in engagement with the periphery of the oscillating control cam 110 which is mounted on the sleeve 71 carried by the shaft 52. The roller is held in engagement with the outer periphery of the cam by means of springs 48 and 49. The bar 47 is provided with a longitudinal slot 115 through which the shaft 52 extends.

As the bar 47 is raised and lowered by the action of cam 110, the rack 107 will cause the gear 106 to rotate, thus rotating the shaft 101 and through the sprocket and gear connections described, rotating the shaft 94. The axis of rotation of the shaft 94 is indicated at X on Fig. 7.

The inner end of the shaft 94 has secured thereto and extending downwardly therefrom, a crank arm 116, to the lower end of which is secured a roller 117 which is guided between an arcuate guiding member 118 and a surface 119 carried by the outer surface of the casing 92.

The crank arm 116 has secured thereto and extending laterally therefrom, a bar or supporting member 125, to the other end of which is secured a vertical downwardly extending bracket 55 or support 126 having a dovetail groove or guide-way 127 (see Fig. 2) in which is vertically adjustable, a bracket 130. The bracket 130 is vertically adjusted by a thumb screw 131 and is locked in adjusted position by a lock screw 133.

The bracket 130 slidably supports, in a manner about to be described, a sleeve 131 which carries the grinding wheel shaft 91. This sleeve is supported between sets of vertical and horizontal rollers. In Fig. 1 there are shown two rollers

135 and 136 which are adjustably mounted and are positioned below the sleeve 131 in which the shaft 91 is mounted. A third roller 138 is also adjustably mounted and engages the upper surface of the sleeve 131 and thus the sleeve is held in vertical position by the two lower rollers 135 and 136 and the upper roller 138. The sleeve is supported against lateral movement in a horizontal plane by two rollers 140 and 141 which engage one side of the sleeve and a third roller 142 which engages the other side of the sleeve,

these rollers all being adjustably mounted in the bracket 130.

Attention is called to the fact that the axis of the shaft 91 which is indicated on Fig. 7 at Z is displaced from the axis X of rotation of the shaft 94. Due to this offset relation between the axes X and Z it will be evident that the oscillation of the shaft 94, by reason of the vertical movement of the bar 47 controlled by the cam 110, will cause the crank arm 116 and the bracket 130 to be oscillated, thus regulating the position of the grinding wheel 90 in such a manner that the point of contact of the grinding wheel with the surface being ground and the axis of rotation of the grinding wheel will be disposed on the radius of curvature of the surface being ground which is drawn from said point of contact to the center of curvature.

As above explained, the cam 70 controls the position of the center of the cam C but the point P or point of contact between the grinding wheel 90 and the surface being ground and the axis Z of the grinding wheel shaft 91 do not lie on a radius about the axis Y of the cam C except when the surface being ground lies in an arc about the axis Y as a center.

Thus, as the center of curvature of the surface being ground changes, the arm 116 carrying the axis Z of the grinding wheel 90 must be swung through an angle in order to bring the points P, Z and X on a radius passing through the new center of curvature. This angle, through which the axis Z must be swung, is the angle F in Fig. 9.

In addition to a rotating movement, the shaft 91 and sleeve 137 are reciprocated in the roller mounting described. The shaft is rotated in the following manner. A cylindrical pulley 150 is mounted on the shaft 91 and is driven by a belt 151 from a grooved pulley 152 mounted on the shaft of a motor 153. The motor 153 is carried by a bracket 154 mounted for vertical adjustment on the casing 92.

The sleeve 137 and shaft 91 are reciprocated in the following manner. The sleeve 137 has secured thereto and projecting laterally therefrom, a plate 155, on the opposite faces of which are positioned rollers 156 and 157 which are carried by a bar 158 which, as shown in Fig. 2, is slidably mounted on the rear face of the casing 92, viewing Fig. 2. The bar 158 has secured thereto a pin 159 which is positioned in a slot 160 formed in the upper end of a link 161, the lower end of which is mounted on a fixed pivot 162. Intermediate its ends the link 161 has mounted thereon a roller 163 which engages the peripheral surface of a cam 164 mounted on a shaft 165 carried by brackets 166. The roller 163 is held in contact with the periphery of the cam 164 by means of a spring 167.

The shaft 165 has mounted thereon a worm wheel 170 which meshes with a worm 171 carried by a shaft 172. Shaft 172 has secured thereto a spur gear 173 which is driven by a gear 174 carried by the shaft 67. Thus the sleeve 137 and shaft 91 will be reciprocated by means of the cam 164 and link 161.

Figs. 9, 10 and 11 illustrate diagrammatically the angular adjustment of the tool support when the surface of the groove in the cam C changes from an arc concentric with the axis of rotation of the cam to arcs drawn about centers eccentric to the center of rotation of the cam C. In Fig. 9 the roller which operates in the cam groove 53 during the use of the cam is indicated at R.

The grinding wheel 90 can be used to grind the outer wall 175 of the cam groove 53 or the inner wall 176 thereof. The position of the grinding wheel 90, in order to grind the inner or outer grooved wall or surface, is determined by the vertical adjustment of the bracket 130.

In the particular cam groove illustrated in Fig. 9, the portion of the cam between the points A and B in an anti-clockwise direction is concentric with reference to the axis of rotation Y of the cam C having the groove being ground. The axis Z of the grinding wheel 90, the axis X of the shaft 94, and the point P of contact between the wheel 90 and surface 175, are located on a radius about Y as a center. However, the portion of the cam groove between the points B and D is drawn on a curve having its center at the point E. In order to maintain the point of contact P between the grinding wheel 90 and the surface being ground between the points B and D, the axis Z of the grinding wheel shaft 91 and the axis X of the shaft 94 on a radius drawn through the center E of curvature of the arc B, D, the position of the axis Z of rotation of the grinder shaft 91 must be angularly displaced and this is accomplished by means of the cam 110 which is so designed that the crank arm 116 will be oscillated in a manner to maintain the point P and the axis Z on the radius 180 drawn between the center of curvature E of the arc B—D and the point P. The angle between a radius passing through the axis Y of the cam C and the axis X of the shaft 94 and between the center of the curvature E of the arc B—D and the axis X, is shown at F. In other words, the angle F represents the angular adjustment necessary to maintain P, Z and X on the radius 180 of the arc B, D. It will be noted that this angle varies from the point B to the point D. Moreover, when the grinding wheel is engaging the portion of the wall 175 between the point D and the point G, the grinding operation is taking place on an arc drawn about the center H. This necessitates a further angular adjustment of the axis Z. The portion of the surface 175 between points G and A has a curvature drawn about the center I.

By means of the particular design of the cam 110, this angular adjustment of the tool support is so regulated that the grinding wheel 90 will be maintained in a position in which the point P and the point Z will always be located on the radius 180 from the point E to the point P when the surface being ground is disposed between the points B and D. When the surface disposed between the points D and G is being ground, the grinding wheel will be so adjusted that the point of contact P between the grinding wheel and this portion of the surface and the axis Z of the grinding wheel will be located on a radius drawn between the center H and the point P.

Furthermore, as hereinbefore stated, whenever the surface 176 is to be ground or finished, the tool is vertically adjusted by the vertical adjustment of the bracket 130 and the angular displacement of the tool support is accomplished in the same manner as that above described.

Referring to Fig. 10, attention is called to the fact that the contour of the cam 70 follows or is the same as the curvature of the surface 176 of the cam C. In Fig. 11 the cam 110 follows the curvature of the path of movement of the axis X of shaft 94. The cams 70 and 110 as shown are larger than the cam surfaces of cam C in order

to obtain greater accuracy in the cam and tool adjustments.

From the foregoing specification it will be clear that by means of the two control cams and the mechanism operated thereby, the walls of a cam groove or any arcuate surface can be evenly and smoothly finished regardless of the displacement of the center of curvature of the arcuate surface from the axis of rotation of the member on which the surface is formed.

Although one specific embodiment of the invention has been particularly shown and described it will be understood that the invention is capable of modification and that changes in the arrangement and in the construction of the various cooperating parts may be made without departing from the spirit or scope of the invention, as expressed in the following claims.

What I claim is:

1. A machine for finishing cam grooves in a cam comprising a support for the grooved cam to be finished, a tool support for rotatably supporting a finishing tool, a rotatable tool mounted on the tool support means for vertically adjusting the support for the cam to be finished, means for rotating said cam, and means for angularly adjusting said tool support to maintain the point of contact between the tool and surface being finished and the axis of rotation of the tool on the radius of curvature of the surface being ground.

2. A machine for finishing cam grooves in a cam comprising a support for the grooved cam to be finished, a tool support for rotatably supporting a finishing tool, a rotatable tool mounted on the tool support automatic means including a control cam for vertically adjusting the support for the cam to be finished, means for rotating said cam to be finished, and automatic means including a second control cam and operative mechanism controlled by said second control cam and connected to the tool support for angularly adjusting said tool support to maintain the point of contact between the tool and surface being finished and the axis of rotation of the tool on the radius of curvature of the surface being ground.

3. A machine for finishing cam grooves in a cam comprising a support for the grooved cam to be finished, a tool support for rotatably supporting a finishing tool, a rotatable tool mounted on the tool support automatic means including a control cam for vertically adjusting the support for the cam to be finished, means for rotating said cam to be finished, and automatic means including a second control cam and vertically adjustable means controlled thereby for angularly adjusting said tool support to maintain the point of contact between the tool and surface being finished and the axis of rotation of the tool on the radius of curvature of the surface being ground.

4. A machine for finishing cam grooves in a cam comprising a support for the grooved cam to be finished, a tool support for rotatably supporting a finishing tool, a rotatable tool mounted on the tool support automatic means including a

control cam for vertically adjusting the cam to be finished, means for rotating said cam to be finished, and automatic means including a second control cam and vertically adjustable means controlled thereby and oscillatable driving connections operated by said vertically adjustable means for angularly adjusting said tool support to maintain the point of contact between the tool and surface being finished and the axis of rotation of the tool on the radius of curvature of the surface being ground.

5. A machine for finishing cam grooves in a cam comprising a support for the grooved cam to be finished, a vertically adjustable tool support for rotatably supporting a finishing tool, a rotatable tool mounted on the tool support automatic means for vertically adjusting the support for the cam to be finished, means for rotating said cam to be finished, and automatic means for angularly adjusting said tool support to maintain the point of contact between the tool and surface being finished and the axis of rotation of the tool on the radius of curvature of the surface being ground.

6. A machine for finishing cam grooves in a cam comprising a support for the grooved cam to be finished, a tool support for rotatably supporting a finishing tool, a rotatable tool mounted on the tool support means for rotating said tool, means for axially reciprocating said tool, automatic means for vertically adjusting the support for the cam to be finished, means for rotating said cam, and automatic means for angularly adjusting said tool support to maintain the point of contact between the tool and surface being finished and the axis of rotation of the tool on the radius of curvature of the surface being ground.

7. A machine for finishing arcuate surfaces in a blank comprising means for supporting a blank having an arcuate surface to be finished, means for supporting a rotatable finishing tool, a rotatable tool mounted on said tool support, automatically operating means for vertically adjusting said support for the blank, means for rotating said blank, and automatically operating means for angularly adjusting the tool support relative to a radius from the point of contact between the tool and surface being finished and the center of rotation of said blank to maintain the point of contact of the tool and said arcuate surface of the blank and the axis of rotation of the tool on the radius of curvature of said arcuate surface.

JOHN VAN BUREN.
